(57) **CLAIM**

I claim the ornamental design of a low profile pump, as shown and described herein.

DESCRIPTION

FIG. 1 is a top perspective view of a low profile pump showing my new design;

FIG. 2 is a bottom perspective view;

FIG. 3 is a side view;

FIG. 4 is an opposite side view of FIG. 3;

FIG. 5 is a top view;

FIG. 6 is a bottom view;

FIG. 7 is a front view; and,

FIG. 8 is a back view.

The broken line showing is for the purpose of illustrating environmental matter and forms no part of the claimed design.
